of horizontal line length, of which the length of each side flap is the same as the width of the box. The box is closed by folding the side flaps over the top flap and the top flap over the side flaps. The top flap is secured to the side flaps by means of adhesive.

UNITED STATES PATENT OFFICE

Patent and Trademark Office, Washington, D. C. Serial No. 139,846, filed January 21, 1950, and Patent No. 2,661,890, issued November 10, 1953.

BOX CONSTRUCTION

William Stastny and Paul Kostelancik, Chicago, Ill., assignors to Lanzit Corrugated Box Company, Chicago, Ill., a corporation of Illinois

Application January 21, 1950, Serial No. 139,846

1 Claim. (Cl. 229—23)

1. The invention relates to improvements in box construction and is more particularly concerned with the construction of a corrugated paper box of sufficient size to enclose a mattress, or the like; the box having integral novel end flaps foldable to close the ends of the box.

It has heretofore been exceedingly difficult and costly to manufacture packages or boxes for large, unwieldy articles such as mattresses. When the box is formed of a single sheet of material scored to facilitate folding, it is difficult to handle the material and to feed it through scoring machines. Also, it is necessary, when manufacturing such a one-piece box, to perform a separate operation in order to slot the ends to provide conventional foldable end flaps. This requires the feeding of the large, unwieldy blank through a second machine. Considerable expense of manufacturing and handling is eliminated when the box is made from two like halves in the manner of the present invention, which halves are of a size to be handled conveniently when fed through a scoring machine and which do not require slotting.

It is an object of the present invention to construct a large box, of the kind having integral end flaps foldable one over the other to close the box ends, from two identical blanks, each of which is easy to handle and feed through the scoring machine.

Another object is to provide a two-piece box construction wherein each piece is scored to define a front and a side panel and end flaps on each end of each panel.

Another object is to provide a mattress box having end flaps scored in such a manner that the box is reinforced when the flaps are folded into and secured in box end closing position.

Another object is to provide a novel method for forming a box of the character described.

Other objects of the invention will appear from the following description and accompanying drawings and will be pointed out in the annexed claim.

In the accompanying drawings there has been disclosed a structure designed to carry out the various objects of the invention, but it is to be understood that the invention is not confined to the exact features shown as various changes may be made within the scope of the claim which follows.

In the drawings:

Fig. 1 is a perspective view of a box open at its ends and embodying the features of the present invention.

Fig. 2 is a fragmentary perspective view of a part of the box shown in Fig. 1, showing the end flaps in a partially folded position.

Fig. 3 is a fragmentary elevational view of the closed box end.

Fig. 4 is a view of one of two like blanks used to form the box of the present invention.

Fig. 5 is a view similar to Fig. 4, showing a modified form of blank.

10 The box 11, shown in Fig. 1, is fabricated from two like blanks 12 of a kind best shown in Fig. 4. Each blank 12 is fabricated from a substantially rectangular sheet of corrugated paper, cardboard, pressboard, or the like, of a size sufficient to constitute one main or front panel and one side panel of the completed box, each panel having end flaps integral with each end. The sheet 12 is fed through a suitable scoring machine to provide therein a longitudinal score line 13 closely adjacent to one edge of the sheet. The score line 13 defines a main or front panel 14 and a side panel 15 when the blank is folded after assembly. After the score line 13 has been provided in the blank, said blank then is turned substantially 90° and is again run through the scoring machine to provide transverse score lines 16, one adjacent to and parallel with each transverse edge of the blank. The score lines 16 are spaced inwardly from the transverse edges of the blank a distance corresponding to the distance at which the score line 13 is spaced from its corresponding blank edge. The score lines 13 and 16 intersect at the ends of the side panel 15. The end portions 17, defined by the transverse edges of the blank and the related score lines 16, constitute flaps adapted to be folded over the ends of the box when the latter is assembled.

40 To assemble the box 11, two blanks 12 are so arranged with respect to one another that the longitudinal free edge of the panel 15 on one blank is complementary to the longitudinal free edge of the panel 14 on the other blank. Suitable strips of adhesive material 18 are laid over the complementary free edges and are secured to the marginal areas thereof so that when the blanks are folded along their score lines 13 a substantially rectangular shallow box of the kind shown in Fig. 1 is provided.

50 It has been indicated hereinabove that the box is particularly constructed to receive a mattress or the like. Obviously, adequate protection of such an article can be attained only when the ends of the box are closed and firmly secured in such manner as to increase the rigidity of the box

as a whole. In order to accomplish this, the end flaps 17 are adapted to be folded over inwardly one upon the other in the manner illustrated in Figs. 2 and 3. Folding of the end flaps 17 is made possible by providing a diagonal score line 19 in each of the end flap portions 21-21' on the ends of the side panels 15. The diagonal score lines 19 extend from the intersections of the longitudinal and transverse score lines 13 and 16 to the related corners of the blank 12. When scored in this manner, one of the end flap portions, for example flap portion 21, of the flap 17 is initially folded inwardly, as shown in Fig. 2, to permit the connected main flap portion 22 on the end of one of the main panels 14 to fold inwardly downwardly substantially at right angles to the plane of the panel 14. Inasmuch as the flap portion 22 has a width corresponding to the width of the side panel 15, its free edge is disposed in substantial abutment with the inside face of the opposed panel 14 of the associated blank. The flap portion 21' on said other blank then is tucked in so as to overlie the previously folded panel flap portion 22 and carry the remaining main flap portion 22' into a position to overlie the previously folded main flap 22. When the flaps are folded in the manner described hereinabove they may be secured in any suitable manner, such as by the application of strips of adhesive-coated material or by stitches. It should be quite obvious that the box is closed tightly at its ends and that the closed flaps tend to reinforce the box against inadvertent collapse.

The blank 23 illustrated in Fig. 5 is substantially like the blank shown in Fig. 4 and like numerals are used to identify corresponding parts thereof. In this instance, the blank has a tab 24 preferably on the longitudinal edge of the side panel 15. When two blanks of this character are assembled in the same manner as the previously discussed blanks are assembled, the tab 24 is folded substantially at right angles to the side panel 15 to overlie the complementary edge of the adjacent panel on the associated blank and stitches or an adhesive may be used to secure the two blanks assembled.

It should be apparent that a box constructed in the manner described hereinabove is inexpensive to manufacture owing primarily to the arrangement of the score lines in the two identical blanks, the use of which avoids any need for the

usual additional machine operations required to slot the end flaps in alignment with the longitudinal score line 13, and that the invention is capable of embodying modifications in its details of construction and assembly without departing from the spirit of the invention or the scope of the appended claim.

We claim:

A box fabricated from two like halves, said halves each comprising a substantially rectangular sheet, a score line in each sheet parallel to and spaced inwardly from one of its longitudinal edges to define a main panel and a side panel on one edge thereof, parallel transverse score lines in each sheet one spaced inwardly from each transverse edge a distance corresponding to the spacing of the longitudinal score line from the aforesaid longitudinal edge to define an end panel on each end of the main panel, said transverse score lines intersecting the longitudinal score line to define with said longitudinal score line corner flap portions, said sheets being folded along all of said score lines so that each sheet comprises a main panel, and a perpendicular side panel and a pair of perpendicular end panels, a diagonal score line in the flap portions of each sheet, strips overlying and securing together complementary longitudinal edges of the main panels and of the side panels when the sheets are folded along the longitudinal score lines and arranged in a box-like formation with the free edge of the side panel on one sheet abutting the free edge of the main panel on the other sheet, said box-like formation being closed at its ends when the respective end panels are folded one over the other, said diagonally scored end flaps being tucked beneath the respective end flaps, and means to secure the box closed.

WILLIAM STASTNY.
PAUL KOSTELANCIK.
